UNITED STATES PATENT OFFICE.

JUSTIN WALZER, OF CHAUX-DE-FONDS, SWITZERLAND.

DOOR SPRING AND LOCK.

SPECIFICATION forming part of Letters Patent No. 360,632, dated April 5, 1887.

Application filed April 5, 1886. Serial No. 197,792. (Model.) Patented in France November 16, 1885, No. 157,918.

To all whom it may concern:

Be it known that I, JUSTIN WALZER, of Chaux-de-Fonds, Switzerland, have invented an Improvement in Combined Door Spring 5 and Lock, (for which Letters Patent were granted to me in France, No. 157,918, November 16, 1885,) of which the following is a specification.

In my improvement the spring acts upon 10 a radius-bar to close the door, said spring being in a barrel within the lock-case, and there is a spring-latch provided with an arm and a notched disk on the spring-barrel, the parts being constructed and placed in such a manner 15 that the arm of the spring-latch rests against the periphery of the disk, and holds the latch in its retracted position, so that the door can close, or nearly so, without the spring-latch having to be pushed back by the nosing, 20 and at this moment the notch of the disk allows the arm of the latch to move so that the latch is projected into the nosing.

By this improvement the slamming of the door is prevented and the latching thereof insured 25 without requiring such a powerful spring to close the door against the resistance of the latch.

In the drawings, Figure 1 is an elevation of 30 the parts within the lock-case, the case itself being in section at the line *x y*, Fig. 2. Fig. 2 is a cross-section at the line *y z*, Fig. 1. Fig. 3 is an elevation of the lock-case, radius-bar, and part of the door; and Fig. 4 is a plan view of the same parts with the door and its 35 posts in section, and also the turn-buckle in section.

The case A is of suitable size and shape. Within it is a bolt, R, that is projected by the spring S.

40 U is the spindle, with an arm, U', and link U' to the shank of the bolt R, for withdrawing such bolt in opening the door; and T T represent the handles upon the spindle U. There may be two handles, or the handle may be only 45 on one side.

The movable lock-plate B is provided, as usual, and within the lock is the spring-barrel C on the axis D. At one end of this axis D is a ratchet-wheel, L, and there is a pawl, 50 M, on the lock-plate, by means of which the power of the spring within the barrel may be

adjusted, and the force applied to close the door thereby regulated.

At one side of the spring-barrel, or formed therewith, is the disk C', which is notched at 55 C", and there is upon the spindle U an arm, Q, the end of which falls into the notch in the spring-barrel at the termination of the movement of the spring-barrel, as hereinafter indicated.

The radius-bar H is attached at one end to the pivot-pillar I upon the door-frame, and the end of this radius-bar passes freely into the lock-case, and it is notched for the reception of the loop of wire cord F, the ends of said 65 cord being fastened to the periphery of the spring-barrel C, and, by preference, there is a turn-buckle, h, upon the radius-bar H, said radius-bar being in two parts, with right and left hand screw-threads passing into the turn-buckle, so as to adjust the length of the radius-bar and cause the notch C" of the disk C' to 70 occupy the proper position when the door is closed.

It will now be apparent that when the handle T is turned and the latch R withdrawn the arm Q is swung away from the notched disk C' and the door can be opened, during which operation the radius-bar H and wire cord F wind up the spring-barrel, and when the door 80 is liberated the spring revolves the barrel, and, acting upon the cord F and radius-bar H, closes the door. During this time, however, the latch R is held back in the position shown in Fig. 1 by the arm Q upon the edge of the 85 disk C' until after the end of the latch R reaches the nosing W; hence the door will close without any resistance by the latch on the nosing, and at this moment the end of the arm Q drops into the notch C" in the disk C, allowing the 90 spring to project the latch into the nosing.

It is preferable to make the spring-latch with an offset, as shown in Fig. 4, so that the mortise in the nosing for the end of the bolt may be a short distance back from the outer edge of 95 the nosing to allow the end of the bolt to slide upon the nosing during the last portion of the movement of the door in closing.

I claim as my invention—

1. The combination, with the spring-barrel 100 and radius-bar, and mechanism, substantially as specified, for connecting the same, of the

notched disk, the spring-latch, the spindle, and the arm Q, substantially as set forth.

2. The combination, with the spring-latch, the spindle, and the arm Q, of a spring-barrel, 5 C, cord F, and radius-bar H, notched at the end to receive the cord, and the notched disk C', acted upon by the spring-barrel, whereby

the spring-latch is held in a retracted position by the arm Q and disk C' until the door is nearly closed, substantially as set forth.

INVENTOR: JUSTIN WALZER.
